UNITED STATES PATENT OFFICE

138,199

DESIGN FOR A FACE POWDER COMPACT

Bernard Kotzin, Los Angeles, Calif.

Application May 6, 1944, Serial No. 113,500

Term of patent 3½ years

(Cl. D86—10)

To all whom it may concern:

Be it known that I, Bernard Kotzin, a citizen of the United States of America, residing in Los Angeles, county of Los Angeles, and State of California, have invented a new, original, and ornamental Design for a Face Powder Compact, of which the following is a specification, references being had to the accompanying drawing, forming a part thereof.

Fig. 1 is a top plan view of a face powder compact showing my new design.

Fig. 2 is a front elevational view of the compact and

Fig. 3 is a side elevational view thereof.

I claim as my invention:

The ornamental design for a face powder compact, as shown.

BERNARD KOTZIN.
